CLAIM

The ornamental design for a speaker, as shown and described.

DESCRIPTION

FIG. 1 is a back perspective view of a speaker, shown in environmental use, showing my new design.

FIG. 2 is a front perspective view thereof, shown with the cover in opened condition.

FIG. 3 is a front perspective view thereof.

FIG. 4 is a front elevational view thereof.

FIG. 5 is a back elevational view thereof.

FIG. 6 is a right side elevational view thereof.

FIG. 7 is a left side elevational view thereof.

FIG. 8 is a bottom plan view thereof; and,

FIG. 9 is a top plan view thereof.

The broken lines in FIG. 1 illustrate environmental subject matter that form no part of the claimed design.

1 Claim, 6 Drawing Sheets

FIG. 1
